UNITED STATES PATENT OFFICE

JOHN HENRY GLENN BAYLES, OF NOTTINGHAM, ENGLAND

CIRCULAR-KNITTING MACHINE

Application filed November 26, 1929, Serial No. 409,856, and in Great Britain December 12, 1928.

This invention relates to improvements in circular knitting machines, and refers to improvements in the means that are provided for adjusting the presser and sinker-cams of such machines. The invention is more particularly applicable to multi-feeder machines fitted with independently operated bearded needles, which latter necessitate the provision at each feeder of an adjustable presser-cam preferably arranged so that it can be put out of action by the automatic mechanism which is provided for stopping the machine when a thread fails or breaks.

In circular knitting machines of this type, three adjustable cams are provided in or on the sinker cam-ring at each yarn feeder, that is, one presser and two sinker-cam elements. These cams are in existing machines adjusted by means of screws located in the body of the sinker cam-ring, and the latter has to be provided with horizontally disposed radial holes to admit the screws. The cam-ring is consequently weakened to a serious extent where the adjusting screws are situated, and has in consequence to be made stronger and heavier than would otherwise be necessary.

According to this invention, the cam adjusting screws for each feeder are located in a housing which is secured on the top of the sinker cam-ring, and the said screws which have inner and outer screw threaded parts of different pitches, are connected by means of screw-threaded sleeves to and actuate approximately radial slides on the underside 30 of the said ring, to which the beforementioned cams are attached. The cam-ring is not with this arrangement weakened in order to accommodate the screws, and in cases where for example three or more adjustment screws are required in connection with each feeder, all the screws at each feeder can be conveniently located in one and the same housing.

Referring to the accompanying drawings. Fig. 1 is a sectional side elevation, and Fig. 2 a plan partly in section, of the cam adjusting means in connection with one feeder of a circular knitting machine, constructed 40 according to our invention.

Fig. 3 is an inverted plan showing the adjustable cams.

Like letters indicate like parts throughout the drawings.

In carrying out this invention, the three cam adjusting screws A, B and C usually provided at each feeder, are disposed in a housing D which is secured on the upper face of the sinker cam-ring E, preferably by means of two vertical screws F, (see Fig. 2) 55 and three approximately radial slides G, H and J, are disposed in recesses in the underside of the said cam ring directly under the housing D. The presser-cam K is secured to the middle slide H, and the sinker-cams L to 60 the two outer ones G and J.

The slides G, H and J are connected to the screws A, B and C, and in order to provide a very fine adjustment, a positive movement in both directions, and a release for the presser cam K, the following construction is adopted. The two outer screws A and C are provided at their outer ends with screw-threads which engage in screw-threaded holes in the housing D, and with a finer screw-threaded part at their inner ends, which engage with screw-threaded sleeves A¹ and C¹ which are also mainly disposed in the housing D. The projecting ends of these sleeves A¹ and C¹ are connected to the cam slides G and J, 70 by means of vertical studs G¹, J¹ which pass up through slots M in the cam-ring E, and are secured in holes provided for them in heads on the projecting ends of the sleeves A¹ and C¹ as shown. The connection described prevents the sleeves A¹ and C¹ from rotating with their respective screws A and C, and it will be appreciated that the extent of the movement imparted to the cam-slides each revolution of the screws, is in the arrangement set forth determined by the difference 75 in the pitches of the two screw-threaded portions thereon.

The presser cam adjusting screw B, is connected to the presser cam-slide H by a similar 85 arrangement to that described, the inner end of the sleeve B¹ associated with the screw B, being connected to the slide H by a stud H¹ on the latter rising through a slot M in the cam ring E and engaging in a hole in the pro- 90 100

jecting end of the said sleeve, but in this case and in order that the presser cam K can be automatically put out of action, the outer screw-threaded portion of the adjustment screw B works in a screw-nut O which slides in a space provided for it in the housing D, and the said nut is held in its inner end or normal position as shown in Figs. 1 and 2 by means of a pivoted catch-lever P, against the action of springs Q and T (see Fig. 1) both of which tends to move the screw B and the cam slide H outward. The catch lever P is pivoted at P¹ to the housing D, and its upper end is connected to the ordinary machine stop mechanism, and when this comes into action owing to the failure of the thread, the lever P is tripped, the sliding nut O is released, and the presser-cam K is moved back by the springs Q and T thereby obviating the pressing off of the work when the thread fails or breaks.

If preferred springs T¹ may be disposed on the sleeve A¹ and C¹ between their enlarged projecting ends and the inner ends of the opening in the housing in which they are disposed, and in this case they only serve to take up any lost motion.

The following provision is made in order to assist in readjusting as required the sinker-cams at each feeder all precisely to the same extent.

Mounted close together on the outer part of each of the screws A and C are a pair of discs R and S, both of which have the same number of divisions set out on their peripheries. The inner discs R which is the larger of the two and is mounted loosely on the screw, has the divisions notched, and a spring plunger V is provided to engage in these notches and prevent the discs R from rotating with the screw. The other outer discs S is connected to and rotates with the screw, and for this purpose it is formed with a sleeve S¹, the latter has a longitudinal slot S² and a projecting pin S³ on the screw engages in this slot. This arrangement permits of the screw moving longitudinally without the disc and at the same time maintains the connection. Both discs are held together close up to the housing and thus prevented from moving longitudinally on the screw by means of studs W fixed in the housing as shown in Figs. 2 and 3.

With the arrangement described, the non-rotating notched discs R can be set to the same reading as the discs which rotate with the screws, and in making a readjustment of the sinker cams, the notched discs R are all turned the same number of divisions, and each of the screws A and C is subsequently turned until the readings agree again. With this arrangement the sinker cams at the respective feeders can all be readjusted from time to time to the same degree without trial and with the minimum risk of error.

What I claim as my invention and desire to secure by Letters Patent is:—

1. In a circular knitting machine, means for adjusting the presser and sinker cams comprising in combination a sinker cam ring, 70 a housing secured on the upper face of the said cam-ring, a series of adjustment screws disposed in the housing said screws having screw-threaded parts engaging in the housing or parts disposed therein, and screw-threaded parts of a different pitch engaging in sleeves which are connected to the respective cam-slides on the underside of the cam-ring, substantially as described.

2. In a circular knitting machine, means 80 for adjusting the presser and sinker cams according to claim 1, in which the screw actuated sleeves are connected to the cam-slides by means of vertical studs on the latter which pass up through slots in the cam-ring and have their upper ends secured in holes provided for them in the projecting ends of the said screw actuated sleeves, substantially as described.

3. In a circular knitting machine, means 90 for adjusting the presser and sinker cams according to claim 1, in which the outer portion of the presser cam adjusting screw works in a screw-nut which slides in the housing and said nut is held against the action of a cam withdrawal spring or springs by means of a catch-lever which can be connected to and tripped by the machine stop mechanism whereby the screw-nut is released and the presser cam withdrawn by the action of the spring or springs, substantially as described.

4. In circular knitting machine presser and sinker cam adjusting means according to claim 1, providing each screw with two indicating discs engraved with the same number of divisions one of which is adapted to rotate with the screw whilst the other is notched and is normally held by a spring catch but is angularly adjustable by hand independently of the screw for the purpose of facilitating the adjustment of the cams at different feeders all to the same extent, substantially as described.

In testimony thereof I have affixed my signature.

JOHN HENRY GLENN BAYLES.
